(57) CLAIM

(21) Appl. No.: 29/461,161

The ornamental design for storage compartment integrally formed with a toilet, as shown and described.

(22) Filed: Jul. 19, 2013

DESCRIPTION

(51) LOC (10) Cl. 23-02

FIG. 1 is a perspective view of the present invention in the closed position; and

(52) U.S. Cl. USPC D23/309

FIG. 2 is a perspective view of the present invention in the open position; and

(58) Field of Classification Search

FIG. 3 is an exterior side view of the present invention in the closed position; and

USPC D23/270-274, 295, 299, 301, 303, 309;

FIG. 4 is an interior side view of the present invention; and

4/460, 300, 315, 449, 464-465, 467;

FIG. 5 is a front view of the present invention in the closed position; and,

D6/663, 664, 664.1

FIG. 6 is a rear view of the present invention in the closed position.

See application file for complete search history.
